UNITED STATES PATENT OFFICE.

PHILIP E. RISHEL, OF WASHINGTON, DISTRICT OF COLUMBIA, ASSIGNOR OF TWO-FIFTHS TO SOLON E. ROSE, OF THE UNITED STATES NAVY; JULIA B. RISHEL ADMINISTRATRIX OF SAID PHILIP E. RISHEL, DECEASED.

INTERNAL-COMBUSTION ENGINE.

1,215,865.

Specification of Letters Patent. Patented Feb. 13, 1917.

Application filed October 22, 1910, Serial No. 588,486. Renewed November 16, 1915. Serial No. 61,856.

To all whom it may concern:

Be it known that I, PHILIP E. RISHEL, a citizen of the United States, residing at Washington, in the District of Columbia, 5 have invented certain new and useful Improvements in Internal-Combustion Engines, of which the following is a specification.

This invention relates to internal combustion engines, particularly of the so-called multiple-piston type, the primary object of the invention being the provision of a simple, compact and efficient internal combustion engine, which shall be well balanced 10 and capable of operating if desired at very high speeds. The engine may be either horizontally or vertically disposed, and of either the two- or four-cycle type. It may comprise one or more power cylinders as 15 desired. In its preferred embodiment the engine comprises a power cylinder having two pistons, and a compression cylinder of larger diameter than the power cylinder and arranged concentrically therewith, one of 20 the pistons having bearing surfaces upon both the power and compressed cylinders. Both pistons are operatively connected to opposite throws of a common crank-shaft. The invention will be illustrated and 25 described as applied to a vertical, single-cylinder engine of the two-cycle type.

For a full understanding of the invention reference is made to the accompanying drawings wherein—

35 Figure 1 is a central vertical section of one form of internal combustion engine embodying the invention;

Fig. 2 is a transverse section on an enlarged scale on the line II—II of Fig. 1;

40 Fig. 3 is a transverse section on an enlarged scale on line III—III of Fig. 1;

Fig. 4 is a fragmentary elevation of the inlet ports;

45 Fig. 5 is a fragmental transverse section through one of the inlet ports;

Fig. 6 is an enlarged longitudinal section of the carbureting device on line VI—VI of Fig. 1; and

Fig. 7 is an elevation of the carbureting device.

The engine illustrated is of the vertical, two-cycle, single-cylinder type, and comprises a power cylinder 1 having a water-jacket 2 mounted within a casing 3 whereof the upper portion 4 is cylindrical and is 55 concentric or co-axial with the power cylinder. The power cylinder 1 has fitted therein with the usual bearing rings upper and lower pistons 5, 6. The piston 6 is directly connected with the crank-shaft 7 by a connecting rod 8. The upper piston 5 is likewise connected with the crank-shaft 7 by means of lateral connecting rods 9—9 at points which are diametrically opposite the point of connection of the rod 8 with reference to the axis of the shaft, the construction being such that the shaft is rotated by the movement of the pistons as they simultaneously approach or recede from each other. The lateral connecting rods 9 are 60 preferably, but not necessarily, incased in housings 10 which may be cast or otherwise formed integral with the fuel compression cylinder 4. As illustrated the power and fuel compression cylinders are mounted upon 65 and carried by a crank-casing 11. The crank-casing is not included in the compression chamber for the incoming gases and is preferably open to the atmosphere as indicated for example at 12—12.

The upper piston 5 is hollow or recessed and opens outwardly into the full compression chamber 13, whereof the recessed body of the piston forms a portion. The inlet ports 14 are disposed around the walls of the 85 power cylinder in alignment with a corresponding number of by-pass recesses 15 formed in the cylinder walls. A like number of radial ports 16 in the walls of the piston 5 near its inner end, are adapted to 90

register with the by-pass recesses 15 as the piston 5 approaches its uppermost or outermost position.

The inlet ports 14 are inclined to radii of 5 the power cylinder 1, as most clearly shown in Fig. 2, and may be substantially tangential to the walls of this cylinder. These inlet ports are preferably contracted and curved laterally at their inner ends as shown 10 in detail in Figs. 4 and 5. The effect of this form and disposal of the inlet ports is to impart a whirling motion to the body of entering gas, whereby such body tends to retain its integrity and to expel the burned 15 gases without appreciably commingling with them.

The exhaust ports 17 comprise a plurality of apertures in the walls of the cylinder 1 in position to be uncovered by the piston 6 20 as it approaches its innermost position. These exhaust ports are preferably of larger size than the inlet ports and are arranged to afford free exit for the burned gases from the periphery of the power 25 cylinder, a preferred arrangement of the ports being as shown in Fig. 3. The inner faces of both pistons are preferably slightly coned as shown, this construction not only aiding in maintaining the whirling motion 30 to the incoming gases, but resulting in a more complete delivery of the burned gases. These effects are attributable to the action of the coned cylinders in centralizing the axis of the rotating body of gas, or in preventing 35 the lateral displacement of this axis which would tend to break or disturb the rotating column, and to afford opportunity for the pocketing of unburned gases.

The upper piston 5 is provided near its 40 outer end with a deep annular shoulder or flange 18, to the lower face of which the lateral connecting rods 9, 9 are attached as indicated at 19. The outer periphery of the shoulder 18 carries piston rings 20 making 45 a gas-tight joint with the inner wall of the compression cylinder 4.

A preferred form of intake valve, mounted upon the compression chamber, is illustrated in detail in Figs. 6—7. In said figures 50 21 represents the valve, mounted to slide upon a threaded stem 22 engaging the wall of the valve-casing 23. A helical spring 24 is carried by the valve-stem and serves to keep the valve normally closed, the 55 compression of the spring being adjustable by rotating the stem 22. A conduit 25 for liquid fuel is mounted upon the valve-casing, and communicates with the valve-seat at a plurality of points around its periphery by means of channels 26 in the casing 60 wall. The conduit 25 carries a closely fitting plunger 27, which is movable longitudinally to uncover successive ports 26 as the conditions of operation may require. 28

indicates a spring-retaining device for the 65 plunger 27, and 29 a series of notches corresponding in position to the several operative positions of the plunger 27.

Ignition is effected as usual, for example by means of a spark plug 30 entering the explosion chamber. 70

The mode of operation of the engine will be readily understood. As the pistons mutually recede and reach the position illustrated in Fig. 1 the exhaust and inlet ports 75 are uncovered, the former preferably slightly in advance of the latter. The combustible mixture which has been compressed in the chamber 13 and the recessed piston 5, is admitted through the inlet ports 14 to the 80 power cylinder, the whirling motion imparted to the incoming gas by the form and arrangement of the ports serving to scavenge the cylinder thoroughly and with but little loss of unburned gases. On the 85 return or mutually approaching stroke of the pistons the gases are compressed in the power cylinder and are ignited when the proper degree of compression is attained. As the outer piston moves inwardly the intake valve 21 is withdrawn from its seat by the suction, thereby permitting the liquid fuel to flow through one or more of the 90 channels 26, in accordance with the position of the plunger 27. The gasoline or other 95 liquid fuel flowing upon the seat of the valve is vaporized by the inflowing air-current. The resulting fuel mixture passes directly to the compression chamber 13 and to the interior of the piston 5 forming a part 100 of this chamber, and is thereby highly heated and very thoroughly gasified. These gases flow directly through the short bypasses 15 to the explosion chamber when the proper phase of the cycle is reached, 105 and enter this chamber at a comparatively high temperature.

The arrangement of the fuel-compression chamber 13, in communication with and including the recessed power piston 5, presents several important advantages. Firstly, the fuel is delivered directly to a heated compression chamber, and is thereby so quickly and thoroughly gasified as to result 110 in important economies of operation; secondly, the incoming gaseous mixture serves to cool the piston to the extent that it absorbs heat therefrom, and thus aids in maintaining the proper working temperature at very high engine speeds; and thirdly, the 115 construction affords a direct and short passage from the compression chamber to the power cylinder, to which the compressed gases are delivered at a high temperature.

The engine may of course be provided 120 with any suitable carbureting or vaporizing device instead of that above described, or may be operated with gaseous fuel. How-

ever by reason of the fact that the gases are compressed within one of the highly heated pistons, the form of intake valve described is particularly adapted for use with the 5 present construction.

The moving parts of the engine are preferably so designed as to secure a substantial balance as between the oppositely moving masses, whereby the pistons may attain high 10 speeds and with but little vibration. A fly-wheel may be used or not as desired. The opposite movement of the pistons secures the effect of very high piston speeds, and the arrangement of the ports is such as to render 15 possible an almost instantaneous discharge of the burned gases, and a correspondingly rapid inflow of the fresh mixture. Under these conditions the engine is economical of fuel, efficient, is not subject to overheating, 20 and is capable of developing a high degree of power in proportion to the weight of metal employed. The engine is readily adapted to the four-cycle mode of operation, and may be constructed of such units and 25 with such number of cylinders as may be desired.

I claim:—

1. In an internal combustion engine, a power cylinder having tangentially directed 30 inlet ports and having two power pistons, a closed compression cylinder for fuel gas co-axial and communicating with said power cylinder and of larger diameter, means for admitting a combustible mixture to the compression cylinder, one of said power pistons having bearing surfaces upon both of said cylinders, a crank-shaft, a central connecting rod operatively connected with one of said pistons, and lateral connecting rods operatively connected with the other of said 35 pistons.

2. In an internal combustion engine, a power cylinder having tangentially directed inlet ports and exhaust ports near opposite 45 ends thereof, a crank-shaft, a power piston in said cylinder operatively connected with said crank-shaft, a closed compression cylinder for fuel gas larger than and communicating with said power cylinder and co-axial therewith, means for admitting a combustible mixture to the compression cylinder, a second power piston having bearing surfaces upon both of said cylinders, and operative connections between said second 50 cylinder and said crank-shaft.

3. In an internal combustion engine, a power cylinder, a closed compression cylinder co-axial with said power cylinder and of larger diameter, means for admitting a 55 combustible mixture to the compression cylinder, a crank-shaft, two power pistons in said power cylinder operatively connected with said crank-shaft, one of said power pistons having a bearing surface in said

compression cylinder, inlet ports communicating with said compression cylinder and disposed near one end of the power cylinder and inclined to radii of the cylinder, and exhaust ports near the opposite end of said power cylinder. 65

4. In an internal combustion engine, a power cylinder having a plurality of inlet and exhaust ports near opposite ends thereof, said inlet ports disposed at an angle to radii of the cylinder, a closed compression 70 cylinder having ports at its lower end and co-axial with said power cylinder and of larger diameter, means for admitting a combustible mixture to the compression cylinder, two power pistons in said power cylinder, one of said pistons having a bearing 75 surface on the compression cylinder, and conduits extending between said compression cylinder ports and said inlet ports.

5. In an internal combustion engine, a power cylinder provided with tangentially directed inlet ports and having two pistons, a closed compression cylinder for fuel gas co-axial with said power cylinder and of 80 larger diameter, means for admitting a combustible mixture to the compression cylinder, means for transferring the mixture when compressed from the compression cylinder to the inlet ports of the power cylinder, one of said power pistons having an 85 annular flange providing a bearing surface in said compression cylinder, a crank shaft, a central connecting rod operatively connected with one of said pistons, and lateral connecting rods secured to the flange of the 90 other piston.

6. In an internal combustion engine, a power cylinder having two power pistons, a closed compression cylinder, means for admitting a combustible mixture thereto, one 105 of said pistons being hollow and having bearing surfaces upon both of said cylinders, said hollow piston having one end open and in communication with said compression cylinder and its other end closed 110 and provided with ports, inlet ports in the power cylinder, conduits arranged to connect the ports in the hollow piston and the ports in the power cylinder when the piston is at the end of its working stroke, a crank-shaft, a central connecting rod operatively connected with one of said pistons, and lateral connecting rods operatively connected 115 with the other of said pistons.

7. In an internal combustion engine, a power cylinder having an open-ended hollow piston, a closed compression cylinder coaxial with said power cylinder, said piston having bearing surfaces upon both said cylinders, means for admitting a combustible 120 mixture into said compression cylinder, ports near the closed end of said hollow piston, and means coöperating with said 125

4
ports for admitting the compressed mixture into the power cylinder and comprising passages in the wall of the power cylinder opening into such cylinder through ports inclined to the radii of the cylinder.

5. In an internal combustion engine, a power cylinder having a piston with a coned inner face and inlet ports disposed near one end of said cylinder so as to be 10 opened at the end of the working stroke, said inlet ports being inclined to radii of the cylinder.

9. In an internal combustion engine, a power cylinder having a plurality of inlet and exhaust ports at opposite ends thereof, ¹⁵ said inlet ports disposed at an angle to radii of the cylinder and two power pistons having coned inner faces.

In testimony whereof, I affix my signature in the presence of two witnesses.

PHILIP E. RISHEL.
